RAIL FLAW DETECTOR MECHANISM

Walter M. Perry, Brooklyn, N. Y., assignor to
Sperry Products, Inc., Brooklyn, N. Y., a cor-
poration of New York

Application May 20, 1936, Serial No. 80,747

4 Claims. (Cl. 175—183)

This invention relates to rail fissure detector mechanism of the type employed on the Sperry rail fissure detector cars. These mechanisms operate upon the principle of passing current through the rail to establish an electromagnetic field surrounding the same and exploring the said field with flux-responsive means, such as induction coils, for the purpose of detecting any irregularities due to the presence of internal fissures. 5 It has been found, however, that the electromagnetic field surrounding the rail is distorted by the presence of other factors as well as internal defects, the said other factors operating to give an indication as of a flaw where in fact none exists. 10 Thus, for instance, since the current is passed into the rail by means of contact brushes as the car runs along the rails, it sometimes happens that these contact brushes make poor contact or lose contact with the rail entirely and there is thereby formed in the surface of the rail a magnetic pole. Such pole distorts the electromagnetic field and is frequently picked up in the same manner as an internal defect. Also, it sometimes happens that surface defects, such as burns on 15 the surface of the railhead, serve to set up local magnetic fields which also are sometimes picked up by the detector mechanism in the same manner as an internal defect. Such actuation of the detector mechanism by surface poles due either to poor contact of the current brushes or to the presence of surface defects such as burns, is undesirable in that it confuses the record and not only slows up the detection operation but frequently causes inaccuracy due to misinterpretation of the record because actual internal 20 defects are mistaken for surface defects.

It is the principal object of my invention, therefore, to provide a mechanism wherein the undesirable effects of factors other than internal 25 defects will be eliminated.

Other objects and advantages of this invention will become apparent in the following detailed description thereof:

In the accompanying drawing,

45 Fig. 1 is a side elevation of a portion of a Sperry rail fissure detector mechanism showing one form of my invention applied thereto.

Fig. 2 is a detail showing a modified form of the invention disclosed in Fig. 1.

50 Fig. 3 is an end view of still another form of my invention.

Referring to Fig. 1 of the drawing, there is disclosed a portion of a Sperry rail fissure detector car which includes a car-body 10 supported on 55 the rail by wheels, not shown, and having sus-

pended therefrom the rail fissure detector mechanism. Said mechanism may be supported on a carriage 11 having flanged wheels 12 whereby it is adapted to ride upon the rail R, the said carriage being normally held in elevated position by means such as cables 13 and springs, not shown, but adapted to be lowered into operating position in engagement with the rail by means of fluid pressure supplied to cylinders 15 to force pistons 16 downwardly against the action of the retractile springs. When the carriage 11 is in operating position in engagement with the rail, it is adapted to supply current to the rail R from a generator G mounted within the car-body 10 and supplying current to spaced sets of brushes 17 and 18 to set up an electromagnetic field surrounding the rail. Said field will be uniform except in the region of flaw, where the field will become distorted. Such distortion may be detected by suitable flux-responsive means such as 20 a pair of connected induction coils 20 oppositely wound so as not to be affected by changes in the current supply. Said coils normally cut the same number of lines of force, but on entering a region of flaw, first one and then the other of the coils 25 will cut a different number of lines of force to generate a differential E. M. F. which after being suitably amplified may be caused to operate any suitable indicator such as a recorder. The coils 20 are supported at a constant distance above 30 the railhead within a housing 21 which is fixed upon a carriage 22 adapted to ride on the rail by means such as sets of wheels 23. The said carriage is supported from the current brush carriage 11 by means such as bolts 24 extending 35 loosely through a bracket 25 fixed to the said carriage 11, said bolts being held in position by means of nuts 27 and springs 26. By this construction the carriage 22 is given a movement independent of the movements of the current 40 brush carriage 11 so that the said detector carriage 22 may at all times follow the contour of the rail surface to maintain the housing 21 and hence the axes of coils 20 always at a fixed distance above the rail surface.

In order that the molecules may be homogeneously aligned by the time the detector coils pass over any given point of the rail, it has been found desirable to premagnetize the rail by means of an additional set of brushes 30 positioned in 50 advance of the brushes 17 and supplied with current from an auxiliary generator G' within the car-body 10, or from an additional winding on the generator G. An auxiliary circuit from brushes 30 through brushes 17 is thus established in ad- 55

vance of and in the same direction as the circuit from brushes 17 to brushes 18, and thus pre-energisation is effected to properly align the molecules, which has been found to result in the coils 20 operating more efficiently to detect a greater number of internal defects.

If any of the cluster of brushes constituting the set 38 or the brushes constituting the set 17 should lose contact or make poor contact with the rail surface, it has been found that there is formed a local magnetic pole which sometimes affects the coils 20 in the same manner as an internal defect and is indicated by the indicating mechanism in the same manner as an internal defect.

Such local magnetic effects are set up not only by reason of poor contact between current brushes and the rail surface, but also by certain dirt spots which have been ground into the rail surface and also by surface burns caused by slipping of locomotive wheels, or the like. These local magnetic disturbances which affect the pick-up coils 20 are undesirable because they result in a multiplicity of false indications, which makes operation more difficult as well as slower and less accurate.

In order to eliminate the effect of magnetic poles formed in the surface of the railhead, I provide the following mechanisms which I have found to be efficient. One such mechanism is disclosed in Fig. 1 and consists in mounting, preferably between the current brushes 17 and the detector carriage 22, a magnetic conductor by-pass 40 which may take the form of a block of steel maintained either in contact with the rail surface or preferably slightly out of contact therewith at a constant distance therefrom. The mounting of the magnetic by-pass 40 may be similar to that of the mounting of coils 21, an additional carriage 22', similar to carriage 22 and similarly mounted on carriage 11, being provided therefor.

The result of positioning the magnetic conductor by-pass 40 close to the rail has been found to be a multiplication of the lines of force threading through the magnetic circuit between the rail surface and the by-pass 40 and concentrating a greater number of lines of flux in the rail surface. This concentration of flux has been found to be sufficient to overcome the local magnetic field which may be set up when a current brush loses contact with the rail or by a dirt spot or by a surface defect. In this manner the local magnetic poles may be readily eliminated so that the induction coils 20 pick up only internal defects.

In a modified form of the invention, the by-pass 40, instead of being merely a magnetizable member such as a steel block, may be a permanent magnet, or it may be an electromagnet 40' as shown in Fig. 2.

Still another modification of my invention is disclosed in Fig. 3. In this form there is inter-

posed between the coils 20 and the rail surface a magnetizable member 40'' which may take the form of a thin plate. The local magnetic field set up by surface defects such as the defect D in Fig. 3, is a permanent magnetic field with a fixed number of lines of flux, and said flux is by-passed by plate 40'' to eliminate the effect of the local flux upon the coil 20 in the same manner as the magnetizable member 40. The plate 40'' has no effect upon the flux surrounding the rail due to the current passing through the rail except that more lines of flux are produced in the field surrounding the rail, the additional lines being concentrated in the plate 40''. To compensate for this additional flux, the coil is moved further away from the rail surface than in the case where plate 40'' is not employed.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a rail flaw detector mechanism, means for energizing the rail with flux, means responsive to variations in flux, and a magnetic conductor positioned adjacent the rail and in advance of said responsive means.

2. In a rail flaw detector mechanism, means for energizing the rail with flux, means responsive to variations in flux, and a magnet positioned adjacent the rail and in advance of said responsive means.

3. In a rail flaw detector mechanism, means for passing current through the rail to establish an electromagnetic field surrounding the same, said means including brushes for leading the current into and out of the rail, means responsive to variations in said field, and a magnetic conductor positioned adjacent the rail between the lead-in brushes and said responsive means.

4. In a rail flaw detector mechanism, means for passing current through the rail to establish an electromagnetic field surrounding the same, said means including brushes for leading the current into and out of the rail, means responsive to variations in said field, and a magnet positioned adjacent the rail between the lead-in brushes and said responsive means.
